UNITED STATES PATENT OFFICE

115,315

DESIGN FOR A WALL CLOCK

Philip Koch, Philadelphia, Pa.

Application April 26, 1939, Serial No. 84,565

Term of patent 14 years

To all whom it may concern:

Be it known that I, Philip Koch, a citizen of the United States of America, residing at Philadelphia, in the county of Philadelphia and State of Pennsylvania, have invented a new, original, and ornamental Design for a Wall Clock, of which the following is a specification, reference being had to the accompanying drawing, forming part thereof.

Fig. I is a front elevation of a wall clock embodying the design.

Fig. II is a side elevation of the same; and, Fig. III is a plan view.

The characteristic features of my design for a wall clock comprise a half axial section of a barrel with bottles as the weights, bottle caps as the hour numerals, and an advertising plaque as the pendulum weight.

I claim:

The ornamental design for a wall clock, substantially as shown and described.

PHILIP KOCH.
